UNITED STATES PATENT OFFICE

161,561

BURIAL VAULT

Max L. Wickersham, Independence, Kans.

Application January 16, 1950, Serial No. 7,287

Term of patent 14 years

(Cl. D19—1)

To all whom it may concern:

Be it known that I, Max L. Wickersham, a citizen of the United States, residing at Independence, in the county of Montgomery and State of Kansas, have invented a new, original, and ornamental Design for Burial Vault, of which the following is a specification, reference being had to the accompanying drawing, forming part thereof.

Fig. 1 is a perspective view of a burial vault, showing my new design.

Fig. 2 is an end view thereof.

Fig. 3 is a plan view of the burial vault.

Fig. 4 is a side elevation thereof.

I claim:

The ornamental design for a burial vault, substantially as shown.

MAX L. WICKERSHAM.
